UNITED STATES PATENT OFFICE.

ANSEL E. FOX, OF LEADVILLE, COLORADO.

ATTACHMENT FOR COAL-OIL CANS.

SPECIFICATION forming part of Letters Patent No. 325,068, dated August 25, 1885.

Application filed April 13, 1885. (No model.)

To all whom it may concern:

Be it known that I, ANSEL E. FOX, a citizen of the United States of America, residing at Leadville, in the county of Lake and State of Colorado, have invented certain new and useful Improvements in Attachments for Coal-Oil Cans, of which the following is a specification, reference being had therein to the accompanying drawings.

This invention pertains to certain new and useful improvements in attachments for coal-oil and other cans for reception of explosive oils, whereby the same are rendered non-explosive; and it consists in the construction, combination, and arrangement of the parts, substantially as hereinafter fully set forth, and pointed out in the claims.

In the accompanying drawings, Figure 1 is a view in side elevation of an ordinary can having my invention applied thereto and showing the spout partly in section, and Figs. 2 and 3 are detail views.

In carrying out my invention I provide the spout A of an ordinary coal-oil or other can with a spherical enlargement or bulb, a, a short distance from the discharge-end, and within this spherical enlargement or bulb I secure therein by ordinary means a metallic gauze screen, a', by which the passage of a flame to the oil contained within said can or receptacle is wholly prevented.

To further provide against the possible passage of a flame to the oil and to permit the admission of air, I provide the screw-cap B with a small metallic screen, b, the object of which is obvious. To the center of the said screw-cap I pivot a movable cover, b', which is designed to fit over and operate on said screw-cap. This movable cover b' has two or more openings or slots provided in its upper surface to register with the openings in the top of the screw-cap; and it is also provided with a small stud or projection, b'', for the convenient opening and closing of the same when desired.

Having thus fully described my invention, what I claim, and desire to secure by Letters Patent, is—

1. In combination with an oil-can having its screw-cap provided with a screen and a movable cover, a spout having a spherical enlargement and a screen, substantially as shown and described.

2. In combination with an oil-can having its spout provided with a spherical enlargement and a screen, the screw-cap having a screen and a movable cover pivoted thereon, substantially as shown and described.

ANSEL E. FOX.
